CLAIM

The ornamental design for a lounge, as shown and described.

DESCRIPTION

FIG. 1 is a front perspective view of a lounge according to one embodiment;

FIG. 2 is a front view thereof;

FIG. 3 is a rear view thereof;

FIG. 4 is a side view thereof, it being understood that both side views are identical; and,

FIG. 5 is a top view thereof.

Features shown in broken lines form no part of the claimed designs.
